FLOWER BOX

Eugene T. Kleine, 87 Ocean Ave.,
Massapequa, N.Y. 11758

Filed Mar. 7, 1972, Ser. No. 232,649

Term of patent 14 years

Int. Cl. D11—02

U.S. Cl. D35—3 R

Fig. 1

Fig. 2

Fig. 4

Fig. 3

Fig. 5

FIG. 1 is a perspective view showing my new design for a flower box;

FIG. 2 is a side view thereof, the other side being a mirror image thereof; the side panel design may vary;

FIG. 3 is a rear view thereof;

FIG. 4 is a top plan view thereof; and

FIG. 5 is a bottom plan view thereof.

I claim:

The ornamental design for a flower box, substantially as shown and described.
